UNITED STATES PATENT OFFICE.

CHARLES H. RAUEN, OF SEATTLE, WASHINGTON.

DISPENSING DEVICE.

1,297,244.

Specification of Letters Patent. Patented Mar. 11, 1919.

Application filed July 28, 1915. Serial No. 41,876.

To all whom it may concern:

Be it known that I, CHARLES H. RAUEN, a citizen of the United States of America, and resident of Seattle, in the county of King 5 and State of Washington, have invented certain new and useful Improvements in Dispensing Devices, of which the following is a specification.

My invention relates to dispensing vessels 10 and consists of a can or jar having a cover or top closing its upper end and provided with means by which small quantities of the contents may be discharged at a time. The object of my invention is to provide means 15 whereby small quantities may be discharged from a container without necessitating using any special individual spoons or other analogous articles to remove the same. The final result desired is to make a device for dispensing products which is thoroughly sanitary and not likely to have foreign particles mixed therewith.

The special features which constitute my invention will be particularly defined by the 25 claims of this specification. In the accompanying drawings I have shown my invention in the forms of construction which are now preferred by me.

Figure 1 is a vertical section through a 30 container having my device incorporated therewith.

Fig. 2 is a vertical section through the upper part of the same device, the same being shown in inverted position.

Fig. 3 is a similar section of the upper 35 part of the device showing the secondary measuring chamber filled with material ready to be discharged when the device is inverted.

Fig. 4 is a section on the line 4-4 of Fig. 1.

Fig. 5 is a vertical section of a container containing my device shown in a slightly modified construction.

Fig. 6 is an inverted vertical section of the same, and

Fig. 7 is a section on the line 7-7 of Fig. 5.

One of the principal uses to which my invention is particularly applicable is in the dispensing of sugar in restaurants and hotels. I have therefore described it mainly as applied to this particular use, although it is to be understood that it may be employed with equal advantage for dispensing any other finely ground or granular mate-

rial, and, in the modification shown in Figs. 5, 6 and 7, it has been especially adapted for dispensing liquids.

The construction and operation of the 60 parts, as shown in Figs. 1 to 4 inclusive, is as follows: C represents a bowl, jar or container of any suitable size having a cap 1 secured thereto and closing its upper end. As herein shown this cap is designed to be 65 secured by threading upon the container. The manner of securing these parts together is, however, immaterial.

Arms 10, depending from the cap, support a ring 11 upon which is secured a cup 70 2, said cup constituting a measuring chamber or vessel. This cup may be secured in place upon the ring 11 by any suitable means, such for instance, as by the frictional grip between the ring and cup, by 75 screwing thereon, or in any other suitable manner. It is preferred that the manner of securing the cup 2 be such that its position lengthwise of the container may be adjusted, as has been indicated by the dotted lines 80 at 20, which indicates the upper adjusted position for the bottom of the cup.

Between the upper edge of the cup, or the upper edge of the ring 11, as the case may be, and the cap 1, a chamber is thus formed 85 which serves as a preliminary measuring chamber for the material being dispensed. Through the cap extends a discharge tube 3, which tube, at its inner end, is flared to form a cone 30. The two parts roughly resembling a funnel which, in the position shown in Fig. 1, is in inverted position. The inner end of this discharge tube projects into the mouth of the cup 2, the mouths or openings of these two parts facing to 90 ward each other. The discharge tube 3 is also preferably adjustable lengthwise of the container, as has been indicated by dotted lines, whereby the lower end edge of the funnel part 30 may be varied in its position relative to the bottom of the cup 2.

The form of construction shown in Figs. 5, 6 and 7 varies from that just described in having a conical flange 4 extending from the top 1 downward and toward the center, 105 the central opening of this being opposite the mouth of the cup 2. As herein shown, the openings of this flange and the cup are of the same size. This relation is, however, not strictly essential.

The ring 11, which sustains the cup 2, is supported from the flange 4, by means of

bars 10, thus forming an annular opening between the ring and the flange 4 through which material may pass from the body of the vessel into the chamber 5 formed in the 5 top by flange 4, which chamber constitutes the preliminary measuring chamber.

Fig. 1 represents the parts in the condition which exists when the container has been newly filled. When this container is inverted 10 the material therein will fall through to what is the lower end of the container, the same being what is normally the top. The material will fill the space between the top 1, the discharge tube 3 and beneath the ring 11, which space constitutes the preliminary measuring chamber.

When the vessel is turned back into normal position the material will fall to the bottom thereof except a certain proportion of 20 the material which is contained within the preliminary measuring chamber 5. This portion of material will pass through the space between the cone 30 and the ring 11 into the cup 2. When the vessel is again inverted a considerable portion of the 25 material contained in the cup 2 will be caught by the flared mouth of the funnel section 30 of the discharge tube 3 and be discharged. At the same time the preliminary measuring 30 chamber 5 is filled so that when the vessel is again righted the cup 2 is again charged.

In handling liquids a slight modification of construction is desirable. This is shown in Figs. 5 and 6 and consists of the conical flange 4. This is necessary in order to direct the liquid with more certainty into the cup 2.

By the use of this device the use of individual spoons for obtaining sugar or any 40 other like goods from the container is obviated. At the same time the vessel is covered so that dirt can not enter. The whole therefore makes a very convenient device which is entirely sanitary.

By mounting the entire measuring apparatus upon the cap and retaining same at what is known as the upper end of the container, packing of the sugar or other material in the container will not interfere with 50 the operation of the device, whereas with the measuring elements placed in the bottom of the container, such packing of the contents will interfere with the work of the measuring apparatus.

Having thus described my invention, what I claim as new, and desire to secure by Letters Patent of the United States of America, 55 is:—

1. A dispensing vessel having a cap, a discharge tube passing through the cap with its receiving opening facing toward the body of the vessel, and a measuring cup within the vessel having its opening facing away from the body of the vessel and surrounding the receiving end of the discharge tube,

said measuring cup and the discharge tube being relatively adjustable to vary the separation of the bottom of the cup and the receiving opening of the tube.

2. A dispensing vessel having a measuring cup open at its upper end and spaced from the top of the vessel, means depending from the top of the vessel for supporting the cup, and a discharging tube extending through the top of the vessel toward the cup, the lower end of the tube terminating below the plane of the upper edge of the cup and spaced from the sides of said cup.

3. A dispensing vessel having a measuring cup open at its upper end and spaced from the top and sides of the vessel, means depending from the top of the vessel for supporting the cup, a discharge tube extending through the top of the vessel and having its lower end terminating in the cup below the top edge of the latter, and means for adjusting the distance between the lower end of the tube and the bottom of the cup.

4. A dispensing vessel having a measuring cup therein, the edges of the cup being spaced from the top of the vessel and the sides of the cup being spaced from the sides of said vessel, means within the vessel for supporting the cup, and a tube extending through one wall of the vessel and its lower end terminating within and below the upper edge of the cup, and spaced from the sides of the cup.

5. A dispensing vessel having a cup therein, the upper open end thereof being spaced from the top of the vessel and the sides being spaced from the sides of the vessel, means for supporting the cup in the vessel, a continuous inclined flange in the top of the vessel extending downwardly and inwardly and terminating above and spaced from the upper edge of the cup to form a guide for the contents of the vessel when the latter is inverted and subsequently turned to normal position, and a tube extending through the top of the vessel and terminating in the cup below the upper edge of the latter.

6. A dispensing vessel having therein a measuring cup spaced from the top and sides of the vessel, a ring engaging the upper open end of the cup, and on which the cup may be vertically adjusted, means for supporting the ring on the inside of the vessel, a tube extending through the top of the vessel and terminating in the cup below the upper edge thereof, the lower end of said tube being spaced from the sides of the cup.

7. A dispensing vessel having therein a measuring cup spaced from the top and sides of said vessel, means for supporting the cup in the vessel, a tube extending through the top of the vessel, the lower end of the tube being flared outwardly and extending

in the cup below the upper edge of the latter and is spaced from the sides of the cup.

8. A dispensing vessel having a measuring cup therein, the edges of the cup being spaced from the top of the vessel and the sides of the cup being spaced from the sides of said vessel, means within the vessel for supporting the cup, and a tube extending

through one wall of the vessel and its lower end terminating in a position to receive material from the cup, and spaced from the sides of the cup. 10

Signed at Seattle, Washington, this 17th day of July, 1915.

CHARLES H. RAUEN.
